UNITED STATES PATENT OFFICE.

EDUARD VON SALIS, OF WINTERTHUR, SWITZERLAND, ASSIGNOR TO BUSCH-SULZER BROS.-DIESEL ENGINE COMPANY, OF ST. LOUIS, MISSOURI, A CORPORATION OF MISSOURI.

ENGINE FUEL PUMP.

Application filed December 12, 1925, Serial No. 75,004, and in Switzerland January 10, 1925.

The object of the invention is to simplify the operation and construction of the fuel injecting means of oil engines, particularly those in which the oil fuel is injected solid 5 or without the aid of high pressure injection air, but without limitation to this or any class of engine. More particularly the invention is an improvement in fuel injection systems of the kind in which so-called accumulators 10 are employed for putting the fuel under pressure to be released at the desired time for injecting the fuel. The invention consists in incorporating the accumulator device in a member which follows the movement of the 15 eccentric or crank which drives the fuel pump and which may be, and preferably is, the pump plunger itself and in the combination therewith of related elements. Various advantages flows from the arrangement which 20 will be made apparent below.

Fig. 1 illustrates the invention in more or less schematic form but sufficient to explain the principle.

Fig. 2 is a circle diagram illustrating the 25 sequence of action.

The pump chamber is provided with a suction or intake valve 1 and a discharge valve 3 which opens to the spray nozzle or injection device 4 of the internal combustion engine. The two valves seat outwardly and are 30 normally closed by a spring although any other style and arrangement of the pump valves could be employed.

The pump plunger 5 is reciprocated by the 35 crank or eccentric 6 on a suitable engine-driven lay shaft as usual and the connection between such shaft and the plunger is constituted by a cross-head structure, in which the accumulator device is carried or with which it 40 is associated so as to produce the effect hereinafter described.

In the form shown the accumulator consists 45 of a helical compression spring 7 contained in a cross-head housing 8 and acting against the head 9 of the pump plunger within the housing. On the inward stroke, it will be seen that the spring is more or less compressed according to the amount of liquid fuel present in the pump chamber when both pump valves 50 are closed. On the outward or suction stroke the plunger is not withdrawn until the housing engages its head 9 and draws it back.

The amount of fuel delivered by the pump is

controlled by the duration of the open period 55 of the suction valve. This valve is opened by the bell crank lever 10 and its spring 11. One end of this crank extends into the path of the plunger crosshead and is arranged so that the valve is open during all the suction stroke 60 and for a part of the compressing stroke, or until the crosshead strikes the bell crank at some point in its compressing stroke and allows it to seat. When the suction valve is thus permitted to seat the advance of the 65 plunger stops, the accumulator spring is compressed by the continuing movement of the crosshead and the fuel remaining in the pump is put under a corresponding pressure.

At the proper time, say at or about compression dead center of the engine, the discharge valve 3 is opened by the cam 12 acting on it through the valve lever 13 and a portion of the fuel then under compression in the 70 pump is thereupon delivered to the injection nozzle 4 under high velocity. The quantity thus delivered is greater or less according as the suction valve was closed earlier or later in the pumping stroke. The time of such closing is subject to variation as by 75 shifting the fulcrum of the suction valve bell crank thus causing earlier or later engagement of the latter by the crosshead. This may be done by hand or it may be done by the engine governor, as indicated in the drawing.

Obviously the details of the leverage 80 above described, whereby the crosshead or pump shaft causes the closing of the suction valve and whereby the discharge valve is 85 opened, are subject to modification to any extent according to circumstances and the preference of the maker. The fuel delivery cam 12 will be understood to be driven by the engine, although the driving connection is not shown. The discharge valve is not influenced 90 by the control exerted by the governor, and may, if preferred, be located directly on the engine cylinder head and close to the combustion space so as to constitute the engine injector valve as well as the pump discharge 95 valve.

In the usual injection system, employing an accumulator spring in which energy is stored during the compression stroke of the pump and the injection takes place on the release of the spring, the discharge or injection valve must be subject to governor control, i. e. its opening must conform to the load and 100 105

speed of the engine. In such case, if the engine is reversed in direction, the parts which are controlled by the governor must also be reversed. This is not necessary with the 5 present invention by reason of the association of the accumulator spring with the plunger operating mechanism and as indicated by the dotted line, the cam nose of the fuel discharge cam 12 is of symmetrical form so that to reverse 10 the engine it is sufficient to reverse merely the starting mechanism.

In the diagram of Fig. 2, the upper arc 14-15 represents the suction stroke; 15-16 the compressing stroke during which excess 15 fuel is returned through the suction valve; point 16 which is variable, represents the time of closing of the suction valve; arc 16-17 represents the continuing stroke of the cross-head, and point 17 represents the opening of 20 the discharge or injector valve, 14 being its point of closing.

Having described the invention the following is claimed:

1. In an airless fuel injection device for internal combustion engines, a combined pump and accumulator comprising a plunger barrel, a plunger, a suction valve, and a delivery valve, in combination with engine-operated 25

reciprocating means to effect through positive means the suction stroke of the plunger, 30 and to effect through resilient means the delivery stroke of the plunger, suction valve lifting means operated by said reciprocating means, control means to vary the point of plunger travel at which said lifting means 35 allows the suction valve to close, and engine-operated means to open said delivery valve.

2. In an airless fuel injection device for internal combustion engines, a combined pump and accumulator comprising a plunger barrel, a plunger, a suction valve, and a delivery valve, both said valves closing outwardly, in combination with engine-operated reciprocating means to effect through positive means the suction stroke of the plunger, and to effect through resilient means the delivery stroke of the plunger, suction valve lifting means operated by said reciprocating means, control means to vary the point of plunger travel at which said lifting means allows the 40 suction valve to close, and engine-operated means to open said delivery valve.

In testimony whereof, I have signed this specification.

EDUARD VON SALIS.
